DESIGN FOR A STOCKING

Otto C. Miller, Philadelphia, Pa.

Application September 28, 1936, Serial No. 65,042

Term of patent 7 years

To all whom it may concern:

Be it known that I, Otto C. Miller, a citizen of the United States, residing at Philadelphia, in the county of Philadelphia and State of Pennsylvania, have invented a new, original, and ornamental Design for a Stocking, of which the following is a specification, reference being had to the accompanying drawing, forming part thereof:

Fig. 1 is a view of a stocking, slightly in perspective, showing my design; and

Fig. 2 is an enlarged fragmentary elevational view bringing out the details of the characteristic feature of the design by the provision of a battlemented band along the side of the arch, the design on the opposite side of the stocking being the same.

I claim:

The ornamental design for a stocking as shown and described.

OTTO C. MILLER.
